(57) **CLAIM**

The ornamental design for an adjustable armature including pivotable knuckle, as shown and described.

DESCRIPTION

FIG. 1 is a perspective view of the claimed design in a first operational orientation;

FIG. 2 is a front elevation of FIG. 1;

FIG. 3 is a top plan view of FIG. 1;

FIG. 4 is a back elevation of FIG. 1;

FIG. 5 is a bottom plan view of FIG. 1;

FIG. 6 is a right side elevation of FIG. 1;

FIG. 7 is a left side elevation of FIG. 1;

FIG. 8 is a perspective view of the claimed design in a different operational orientation; and,

FIG. 9 is a perspective view of the claimed design in a still different operational orientation.

The broken lines in the drawings illustrating unclaimed portions of the design form no part of the claimed design.
